BAG OF OPEN-MESH MATERIAL AND PAPER

Charles V. Brady and August F. Ottinger, St. Louis, Mo., assignors to Bemis Bro. Bag Company, St. Louis, Mo., a corporation of Missouri

Original application October 9, 1948, Serial No. 53,708. Divided and this application March 9, 1951, Serial No. 214,794

7 Claims. (Cl. 150—1)

1

This invention relates to bags made of open-mesh material and paper, and with regard to certain more specific features, to ventilated bags of this class.

This application is a division of our copending application, Serial No. 53,708, filed October 9, 1948, entitled Bag of Open-Mesh Material and Paper, and issued August 28, 1951, as Patent No. 2,565,754.

Among the several objects of the invention may be noted the provision of an improved ventilated bag of the class described having a relatively large area of imperforate material suitable for printing labels on the bag; the provision of a bag of the class described which has excellent strength and which provides for excellent visibility of products carried therein; the provision of a bag of this class which may be formed in part of open-mesh fabric adapted for incorporation of a woven-in draw cord; and the provision of a bag such as described which may be manufactured at low cost.

In general, a bag constructed in accordance with the invention has, among its principal features, a top section of open-mesh material in the form of a band forming the upper part of the bag body with the upper edge of this band defining the mouth of the bag, and a bottom section of paper in the form of a band forming the lower part of the bag body having its upper edge portion overlapping and secured to the lower edge portion of the open-mesh section, the bottom section having its bottom closed to form the bottom of the bag. Other features will be in part apparent and in part pointed out hereinafter.

The invention accordingly comprises the elements and combinations of elements, features of construction, and arrangements of parts which will be exemplified in the structures hereinafter described, and the scope of which will be indicated in the following claims.

In the accompanying drawing, in which several of various possible embodiments of the invention are illustrated,

Fig. 1 is a plan view of a bag embodying the invention;

Fig. 2 is an enlarged section taken on line 2—2 of Fig. 1, thicknesses being exaggerated;

Fig. 3 is an enlarged fragmentary section taken on line 3—3 of Fig. 1, thicknesses being exaggerated; and,

Fig. 4 is a section similar to Fig. 2 illustrating a modification.

Similar reference characters indicate corresponding parts throughout the several views of the drawings.

Referring to Figs. 1—3 of the drawing, a bag of this invention is shown generally to comprise a bottom section or band 51 of paper forming the lower end of the bag entirely, and a top section or band 53 of open-mesh fabric material forming the upper end of the bag. As more particularly shown in Fig. 2, the paper section 51 consists of two plies of paper, the outer ply being designated 55 and the inner ply 57. The paper may be of any suitable variety, such as kraft paper or, if desired, creped paper. The open-mesh fabric may be of any open-mesh variety such as is ordinarily used in bag manufacture, for example a leno or plain weave.

The open-mesh top section 53 of the bag is in the form of a girthwise band forming the upper part of the bag body, with the upper edge 59 of the band defining the mouth of the bag. This open-mesh section is shown in Fig. 1 as having a draw cord 61 woven therein adjacent the mouth edge. The two-ply paper bottom section 51 is in the form of a band forming the lower part of the bag body, and has its bottom closed to form the bag bottom. The lower edge portion of the open-mesh top section is sandwiched between the upper edge portions of the two paper plies and is secured therein, preferably by adhesive as indicated at A. The lower edge of the open-mesh section 53 is designated 62. It will be seen that the upper edge portion of the outer paper ply 55 overlaps the lower edge portion of the top section on the outside, and the upper edge portion of the inner paper ply 57 overlaps the lower edge portion of the top section on the inside.

The bag shown in Figs. 1 to 3 may be made in production by combining a continuous web of open-mesh material with two continuous webs of paper, one longitudinal marginal edge of the open-mesh web being sandwiched between the paper webs at one longitudinal edge portion thereof, and adhered therein to form a composite continuous web. The open-mesh web may have a draw cord woven therein extending longitudinally adjacent the other marginal edge of the open-mesh web. Then this composite web (including the draw cord) is severed along transverse lines spaced apart a distance corresponding to twice the width of the bags which are to be formed. Each blank thus obtained is of generally rectangular form and consists of a generally rectangular top section of the open-mesh material which extends the full width of the

blank but only part of its height (about one-half its height as illustrated in Fig. 1), and a separate generally rectangular bottom section consisting of two plies of paper, this paper section also extending the full width of the blank and the remainder of its height. In the blank, the open-mesh and paper sections are arranged with the lower widthwise marginal edge portion of the open-mesh section sandwiched between and secured to the paper plies at the upper widthwise marginal edge portion thereof. As above stated, this securing is preferably by adhesive. The blank is folded upon a fold line, indicated at 63 in Figs. 1 and 2 which extends heightwise across both the open mesh section and the two-ply paper section to bring the marginal edges of the blank into substantial coincidence. Preferably, the edges of the folded blank opposite the fold and at the paper end of the folded blank are turned or folded in and stitched together by stitching 65 thereby to seam these edges together thereby to form side and bottom seams. While a folded-in type of seam is illustrated, it will be understood that other types of seam may be employed. Such turning under of the edges as illustrated provides for a better anchor between the stitching of the side seam and the open-mesh weave of the fabric. In addition, such turning under aids the anchoring which is desired at 67 between the ends of the draw cord 61, so that the opposite portion of the draw cord at 68 may now be pulled for closing the bag mouth. Such turning under also forms a finished bag without the necessity of turning it inside out.

The above described operations result in the formation of the open-mouthed draw cord bag illustrated in Fig. 1 having the open-mesh section 53 forming a ventilating panel at the upper end of the bag, and having a paper bottom constituted by the two-ply paper section 51. This bottom is closed by the bottom reach of the seam 65. The paper section provides adequate area for imprinting labels.

Fig. 4 illustrates a modification which is in all respects like the modification illustrated in Figs. 1 to 3 except that the inner paper ply 51 is omitted. In this form of bag, therefore, the paper bottom section consists only of a single ply of paper 55, and this overlaps the lower edge portion of the open-mesh section on the outside, and is secured thereto, preferably by adhesive A. In all other respects, the modification shown in Fig. 4 is exactly the same as that shown in Fig. 1.

The above-described bag constructions have several advantages over prior ventilated bags. For example, they have an advantage over other essentially paper bags with an open-mesh window insert. This is because the provision of a complete peripheral tubular section or band of open-mesh material enhances strength. In addition, the use of such a tubular section of open-mesh material at the top of the bag with the woven-in draw cord facilitates the provision of such a draw cord. In addition, the draw cord is not required to pucker any paper, but merely puckers open-mesh fabric. Also the peripheral tubular band of paper provides an economical label-forming area.

Thus, this invention provides a ventilated bag having a relatively large area of imperforate material (the full area of the paper section 51) suitable for printing labels and a perforate area (the full area of the open-mesh section 53) for visibility and for ventilating the bag contents. The above-described bags are economical to man-

ufacture because they are formed in part of relatively inexpensive paper and thus require less of the relatively expensive open-mesh fabric than prior ventilated bags formed entirely of open-mesh fabric, and because of being capable of manufacture by a simple process.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

We claim:

1. A bag comprising a top section of open-mesh material in the form of a band forming the upper part of the bag body with the upper edge of said band defining the mouth of the bag, and a bottom section consisting of two plies of paper in the form of a band forming the lower part of the bag body, the lower edge portion of the said upper open-mesh band being sandwiched between the upper edge portions of the plies of said bottom section and secured therein, the bottom of the said bottom section being closed to form the bag bottom.

2. A bag as set forth in claim 1 wherein the edge portion of the open-mesh section sandwiched between the two paper plies is adhesively secured thereto.

3. A bag formed of a generally rectangular blank comprising a generally rectangular top section consisting of open-mesh material extending the full width of the blank but only part of its height, and a separate generally rectangular bottom section of paper extending the full width of the blank and the remainder of its height, said sections being arranged with the lower widthwise marginal edge portion of the open-mesh section and the upper widthwise marginal edge portion of the paper section overlapping and secured together, thereby uniting the sections to form the blank, the blank being folded upon a fold line which extends heightwise across the open-mesh section and the paper section to have the marginal edges of the blank substantially coincident, the coincident edges of the folded blank opposite the fold and at the paper end of the folded blank being seamed to form an open-mouthed bag having a ventilating panel at its upper end formed by the open-mesh section, and having its bottom consisting of paper.

4. A bag formed of a generally rectangular blank comprising a generally rectangular top section consisting of open-mesh material extending the full width of the blank but only part of its height, and a separate generally rectangular bottom section consisting of two plies of paper, said paper section extending the full width of the blank and the remainder of its height, said sections being arranged with the lower widthwise marginal edge portion of the open-mesh section sandwiched between and secured to the paper plies at the upper widthwise marginal edge portion thereof, thereby uniting the sections to form the blank, the blank being folded upon a fold line which extends heightwise across both the open-mesh section and the two-ply paper section to have the marginal edges of the blank substantially coincident, the coincident edges of the folded blank opposite the fold and at the paper end of the folded blank being seamed to form an open-mouthed bag having a ventilating panel

at its upper end formed by the open-mesh section, and having a paper bottom.

5. A bag as set forth in claim 4 wherein the edge portion of the open-mesh section sandwiched between the two paper plies is adhesively secured thereto.

6. A bag formed of a generally rectangular blank comprising a generally rectangular top section consisting of open-mesh material extending the full width of the blank but only part of its height, and a separate generally rectangular bottom section of paper extending the full width of the blank and the remainder of its height, said sections being arranged with the lower widthwise marginal edge portion of the open-mesh section and the upper widthwise marginal edge portion of the bottom section overlapping and adhesively secured together, thereby uniting the sections to form the blank, the paper section overlapping the open-mesh section on the outside thereof, the blank being folded upon a fold line which extends heightwise across the open-mesh section and the paper section to have the marginal edges of the blank substantially coincident, the coincident edges of the folded blank opposite the fold and at the paper end of the folded blank being inturned and stitched together to form an open-mouthed bag having a ventilating panel at its upper end formed by the open-mesh section, and having a paper bottom.

7. A bag formed of a generally rectangular blank comprising a generally rectangular top section of open-mesh material extending the full width of the blank but only part of its height,

and a separate generally rectangular bottom section consisting of two plies of paper, the bottom section extending the full width of the blank and the remainder of its height, said sections being arranged with the lower widthwise marginal edge portion of the open-mesh section sandwiched between and secured to the paper plies at their upper widthwise marginal edge portion, thereby uniting the sections to form the blank, the blank being folded upon a fold line which extends heightwise across both the open-mesh section and the paper section to have the marginal edges of the blank substantially coincident, the coincident edges of the folded blank opposite the fold and at the paper end of the blank being inturned and stitched together to form an open-mouthed bag having a ventilating panel at its upper end formed by the open-mesh section, and having a paper bottom.
